UNITED STATES PATENT OFFICE.

EDWARD R. VASCONCELLOS, OF CHICAGO, ILLINOIS.

TOY SHOOTING-GALLERY.

1,361,119.

Specification of Letters Patent.

Patented Dec. 7, 1920.

Application filed February 15, 1919. Serial No. 277,227.

To all whom it may concern:

Be it known that I, EDWARD R. VASCONCELLOS, a citizen of the United States, and a resident of the city of Chicago, county 5 of Cook, and State of Illinois, have invented certain new and useful Improvements in Toy Shooting-Galleries, of which the following is a specification.

My invention relates to improvements in 10 toy shooting galleries, and has for its object the provision of a device of this character which will be of durable and economical construction and which will afford considerable amusement and entertainment 15 for the users thereof.

Other objects will appear hereinafter.

The invention consists in the combinations and arrangements of parts herein- 20 after described and claimed.

The invention will be best understood by reference to the accompanying drawings forming a part of this specification, and in 25 which,

Figure 1, is a perspective view of a device embodying the invention, and,

Figs. 2 and 3, sections taken on substantially lines 2—2 and 3—3, respectively, of Fig. 1.

The preferred form of construction, as 30 illustrated in the drawings, comprises an elongated handle 5 formed of a single piece of wire bent upon itself and having its ends twisted together. Said handle, at one end, is bent downwardly as at 5' to afford 35 a better grip in using the device. At the opposite end of said handle, the wire is formed into a rectangular loop 6, which supports a plate or holder 7 having its ends wrapped around said loop 6, said plate being 40 thus disposed at right angles to handle 5.

Arranged at the rearward side of plate 7 is a target 8 having a lip 9 at its upper side loosely embracing the central portion 45 of the upper side of loop 6. The arrangement is such that the target 9 is swingingly associated with the plate 7, said target being adapted to swing from a position directly behind the plate 7 to one above said plate, 50 as seen in dotted lines in Fig. 2. The lip 9 is extended to constitute a stop 10 for limiting upward swinging of the target, the arrangement being such that said target is permitted to swing just past the vertical position when the same will, by gravity, be held in this position. The plate 7

is provided with a central opening 11 with which the target registers when in lowered position, as seen in full lines in the several views.

Extending across the front side of plate 7 is a rubber band 12 having its ends secured to integral ears 13 formed upon said plate at opposite sides thereof, the arrangement being such that the band 12 extends 60 centrally across the opening 11. Connected centrally with the band 12 is a second rubber band 14, the free end of which is provided with a knot or other suitable hard member 15.

In using the device, the grip 5' is held in one hand and the member 15 grasped in the other and drawn back or retracted against the tension of rubber bands 12 and 14. After the member 15 has thus been drawn back or 70 retracted, the same is released, the tension of bands 12 and 14, upon release of said member 15, causing the latter to be carried forwardly so as to pass through the opening 11 and strike the target 8 with considerable impact. 75 This causes the target to be swung rearwardly and upwardly, the endeavor of the user of the device being to strike the target with just sufficient force to cause the same to be moved to its upright position, as shown 80 in dotted lines in Fig. 2. If the member 15 is not retracted sufficiently, the same will not strike the target with sufficient force to carry the same upwardly to the desired position. If said member 15 is retracted too far, the 85 target will be struck with such force that the same will swing its entire distance upwardly and will rebound so as to again assume initial position. The skilful player is the one who can strike the target with just the proper 90 force to cause the same to swing to and remain at its upper terminal of movement. Much entertainment and amusement is experienced by players endeavoring to obtain 95 this result.

From the use of the device as described, it will be seen that the member 15, and, to a certain extent, also the member 14 constitute the projectile which, in the use of the device, will be propelled or actuated through 105 the resiliency or elasticity of bands 12 and 14. The target 8 may be provided with any suitable decoration or likeness desired.

While I have illustrated and described the preferred form of construction for carrying 110 my invention into effect, this is capable of variation and modification without depart-

ing from the spirit of the invention. I, therefore, do not wish to be limited to the precise details of construction set forth, but desire to avail myself of such variations and 5 modifications as come within the scope of the appended claims.

Having described my invention, what I claim as new and desire to secure by Letters Patent is:—

- 10 1. A toy of the class described comprising a handle formed of a single piece of wire bent upon itself and having its ends twisted together; a holder held in the central portion of said wire and disposed at substantially right angles to said handle; a target swingingly mounted on said holder; a projectile engageable with said target to move the same from one position to another; and resilient means connecting said projectile and holder, 15 said holder being cut away to permit of said projectile striking said target, substantially as described.
- 20 2. A toy of the class described comprising a handle formed of a single piece of wire bent upon itself and having its ends twisted together; a thin flat plate held in the central portion of said wire and disposed at substantially right angles to said handle; a swingingly mounted target arranged adjacent said 25 plate and adapted, in one position, to be disposed behind said plate; a projectile engageable with said target to move the same from 30

one position to another; resilient means connecting said projectile and plate; and integral ears on said plate for engagement by 35 said resilient means, said plate having a central opening to permit of said projectile striking said target, substantially as described.

3. A device of the class described comprising a frame; a handle projecting at right angles from said frame; a holder mounted on said frame; a target swingingly mounted on said holder; and a projectile yieldingly connected with said holder and adapted to contact with said target to swing the same from one position to another, substantially as described. 40

4. A toy comprising a frame; a handle projecting from said frame at right angles 45 thereto and integral therewith; a holder mounted on said frame; a target swingingly mounted on said holder; and a projectile yieldingly connected with said holder and adapted to contact with said target to swing 50 the same from one position to another, substantially as described. 55

In testimony whereof I have signed my name to this specification in the presence of two subscribing witnesses.

EDWARD R. VASCONCELLOS.
